UNITED STATES PATENT OFFICE.

WALTER L. BRADSHAW, OF CAMBRIDGE, MASSACHUSETTS.

CORD-GRIP FOR PENDANT LIGHTS OR OTHER FIXTURES.

SPECIFICATION forming part of Letters Patent No. 781,764, dated February 7, 1905.

Application filed May 27, 1904. Serial No. 210,000.

To all whom it may concern:

Be it known that I, WALTER L. BRADSHAW, a citizen of the United States, and a resident of Cambridge, in the county of Middlesex and 5 State of Massachusetts, have invented a new and useful Improvement in Pendant Electric Fixtures, of which the following is a full, clear, and exact description, reference being had to the accompanying drawings, forming 10 a part of this specification, in explaining its nature.

My invention has reference to electric fixtures suspended by the conducting-cord, and relates particularly to means for preventing 15 the stripping of the cord from the terminal binding-posts by the weight of the fixture. Such stripping is ordinarily prevented by knotting this cord within the rosette or socket, although in my copending application, Serial No. 171,309, I have shown more efficient 20 means for accomplishing this purpose.

My present invention, like that of my aforesaid application, relates to means adapted to be attached to or formed a part of a rosette, 25 a lamp-fixture socket, or the like and is adapted to secure and engage the cord, thereby throwing the weight of the lamp-fixture upon the body of the rosette or upon the wire conducting-cord instead of upon the binding- 30 posts. More particularly, however, my invention relates to lamp-supporting means which are adapted to be connected to conducting-cords of varying sizes, such means being adapted to positively engage the conducting- 35 cord without any more careful or exact manipulation than would be called for by an ordinary electrician or inspector in the performance of that work.

My invention involves the construction of 40 a conducting-cord clamp the elements of which are simple and the material cheap and of non-absorbent and non-resilient material, whereby the device is durable and does not lose its efficiency without a considerable lapse 45 of time.

Having briefly set forth the object of my invention, I will now proceed to describe the same, reference being had to the accompanying drawings, in which—

50 Figure 1 is a side elevation of my device,

the parts being assembled, but detached from the conducting-cord. Fig. 2 is a similar view of the main element or body of my device, the same being a hollow member provided with a threaded extension for attachment to a 55 rosette or lamp-socket. Fig. 3 is a side elevation of another element of my device, which is adapted to be fitted within and to serve as a bushing in the threaded extension of the body member shown in Fig. 2. Fig. 4 is a 60 side elevation of a loose element adapted to operate and to clamp a wire conducting-cord within the hollow member shown in Fig. 2. Fig. 5 is a side elevation of a bushing through 65 which the cord passes in the top or cap portion of my device shown in Fig. 6. Fig. 6 is a similar view of a cap or an adjusting member for controlling the position of the clamping member shown in Fig. 4. Fig. 7 is a top plan view of the member shown in Fig. 3. 70 Fig. 8 is a view in cross-sectional elevation, showing my device in operative position and as attached to an ordinary ceiling-rosette; and Fig. 9 is a view in elevation, partly in section, showing my device assembled and in operative 75 position as attached to an ordinary Edison lamp-socket.

Referring to the various figures, the tubular piece or cup 1, as shown, is provided with a threaded extension 2 for engagement with a 80 ceiling rosette or lamp-socket piece. The piece 1 is also shown as having a neck threaded at 3 for engagement with a second tubular piece or cap 4. A bushing or piece 5 (shown in detail in Fig. 3) is adapted to fit closely 85 within the neck or piece 1, and a bushing or piece 6, provided with a shoulder 7, is adapted to fit within an opening 8 in the cap 4 to engage the cap at the shoulder, as shown in Figs. 8 and 9. The pieces 5 and 6 are shown 90 as slightly rounded at their inside edges to prevent abrasion of the cord on contact therewith. The piece 1 is shown as provided with an internal strip of insulation 9.

Within the cap or casing 1 is a member 10 95 of a size to permit it to be freely rolled or moved within the casing and to permit the cord to pass between it and the wall of the casing when the device is in operation. This member is shown as a ball or marble; but so 100

it is adapted to operate in the manner herein described and claimed its form is not material.

The pieces 1 and 3 are preferably of brass or similar material, the pieces 5 and 6 of porcelain, and the marble of clay, although it is apparent that the material of the parts may be varied within wide limits.

The assemblage and operation of my device is as follows: The piece 6 is fitted within the cap 4 and the cord passed through the opening therein. The piece 5 is fitted within the cup 1 and the cord passed through the opening in the piece 5. The cup 1 is then screwed into the ceiling rosette or socket and the terminals of the cord properly screwed to the binding-post. The movable member or ball 10 is then pushed into the cup 1 and the cap 4 secured onto the cup. The cap 4 engages the shoulder of the piece 6, and the latter co-acting with the member 10 kinks the cord at the point of contact, as shown in Figs. 8 and 9, in which position the cord is firmly held from longitudinal movement through the device. The action of the several members in thus retaining the cord immovable is wedge-like. In Fig. 8, for instance, any pull upon the cord only serves to wedge the marble more tightly between the wall of the body member 1 and the opposing edge of the member 5, whereas in Fig. 9 any pull upon the fixture only serves to force the member 10 more tightly between the wall of the body member and the opposing edge of the member 6. The cord and marble are maintained from direct contact with the body or cup member 1 by insulating-strip 9, which thus acts to prevent any short-circuiting through the fixture. It will be seen that any pull upon the cord only tends to force the cord and marble more closely into contact and prevent any yielding of the cord impossible. In the case of braided cords the member 10 will lie over the line of the strands and will cause the strands to lie side by side between it and the body-piece 1 instead of lying over each other, in which position they might be injured by pressure or strain. It is to be noted that the pressure of the clamping means upon the cord is not entirely transverse to the line of strain, as is the case in certain other clamping devices, but that the cord is kinked and the pressure distributed along the bend. The cord being jammed between the marble and the rounded inside edges of the pieces 5 and 6 may be said to be positively engaged by these elements, such engagement being thus distinguished from simple frictional engagement such as might be produced by ordinary clamping-jaws.

It is obvious, furthermore, that my clamping device is not limited for use with any particular size of cord, but by its very nature is adjustable to operatively engage cords of widely-varying sizes. Furthermore, owing to the nature of my clamping device and to the

fact that any pull upon the cord only serves to force the marble into a more efficiently clamping position it is apparent that the cap 4 need not be screwed down to the limit of its movement upon the piece 1, but will effectively cause the clamping of the cord, even although only partly screwed down. This loose fit is of great practical importance, for the reason that careless operation of electrical fixtures by inspectors and electricians often leaves the fixtures loosely assembled, and consequently, perhaps, inoperative and dangerous.

Although I have shown my device constructed in five pieces of definite shape, this precise construction is not essential, as it is obvious that certain of the pieces—for instance, the pieces 5 and 6—may be made integral with the pieces 1 and 4 or may be omitted altogether, provided the pieces 1 and 4 are altered in form to answer the function of the absent parts.

Various other modifications in structure without departing from the spirit of my invention will be apparent.

Having thus fully described my invention, I claim and desire to secure by Letters Patent of the United States—

1. A device for relieving the strain on the terminals of electric wires, consisting of a hollow shell or casing to embrace the conducting-cord, means for attaching the shell or casing to a suitable support, and a grip adapted to roll in the casing and to bind the conducting-cord to said shell or casing with a wedging action.

2. In a device of the character described, a hollow shell or casing provided with means of attachment to the support for the electric-wire terminals, such hollow casing having a passage therethrough for the wire conducting-cord, a rolling member located within said hollow case, and means for controlling the position of the rolling member to cause the cord to be clamped in the casing with a wedging action.

3. In a device of the character described, a hollow shell or casing provided with means of attachment to the support for the electric-wire terminals, such hollow shell or casing having a passage therethrough for the conducting-cord, a marble or spherical member movable within the casing, and means for controlling the position of said spherical member to cause the cord to be clamped within the casing.

4. In a device of the character described, a hollow casing provided with means of attachment to the support for the electric-wire terminals, said casing having a passage therethrough for the conducting-cord, a movable member within said casing and means adjustably engaging the casing and controlling the position of the movable member and to cause the cord to be clamped between the movable member and the casing.

5. In a device of the character described, a shell or casing provided with means of attachment to the support for the electric-wire terminals, such shell or casing having an opening for the passage of a cord, a movable member loosely supported within said casing and means surrounding the cord to control the position of the movable member to cause the casing to be clamped to the cord.
10. 6. In a device of the character described, a shell or casing provided with means of attachment to the support of the electric-wire terminals, said shell or casing having an opening for the passage of the conducting-cord for the wires, a movable member loosely supported within said casing and means adjustably engaging the casing to limit the play and to control the position of the movable member to cause the casing to be clamped to the cord.
15. 7. In a device of the character described, a casing provided with means of attachment to the support of the electric-wire terminals, said casing having a passage therethrough for the conducting-cord for the wires, a rolling member within said casing and means for controlling the position of said member to cause the alinement of the cord within the casing to be kinked or interrupted and the cord to be

clamped within the casing by a wedge action of said member.

8. In a device of the character described, a casing provided with means of attachment to the support for the electric-wire terminals, said casing having opposing openings therein for the conducting-cord, a rolling member within said casing and means for controlling the position of said member to cause the alinement of the cord between said openings to be kinked or interrupted, and the cord clamped within the casing whereby the whole device is firmly attached to the cord.

9. A device for relieving the strain on the terminals of electric wires, consisting of a hollow shell or casing to embrace a conducting-cord, said shell or casing having an interior insulating strip or hoop, means for attaching said casing to a suitable support and a grip loosely supported and freely movable within the casing and means adapted to cause the grip to bind the conducting-cord against the insulation of the casing with a wedging action, substantially as described.

WALTER L. BRADSHAW.
